FIG. 12.

FIG. 1 is an isometric view of the bottom and front of the desoldering tool embodying the design of my invention;

FIG. 2 is a side elevational view of this desoldering tool, the opposite side being the same;

FIG. 3 is a front elevational view of this desoldering tool;

FIG. 4 is a top elevational view of this desoldering tool;

FIG. 5 is a bottom elevational view of this desoldering tool;

FIG. 6 is an isometric view of the bottom and front of another embodiment of the desoldering tool illustrated in FIG. 1;

FIG. 7 is a side elevational view of the desoldering tool illustrated in FIG. 6;

FIG. 8 is a front elevational view of the desoldering tool illustrated in FIG. 6;

FIG. 9 is a top elevational view of the desoldering tool illustrated in FIG. 6;

FIG. 10 is a bottom elevational view of the desoldering tool illustrated in FIG. 6;

FIG. 11 is an isometric view of the bottom and front of another embodiment of the desoldering tool illustrated in FIG. 1 and FIG. 6 wherein the only difference resides in the enlargement of the lowest cylindrical element over the form shown in FIG. 6;

FIG. 12 is an isometric view of the bottom and front of still another embodiment of the desoldering tool illustrated in FIG. 1, FIG. 6 and FIG. 11 wherein the only difference resides in the further enlargement of the lowest cylindrical element over the form shown in FIG. 6.

I claim:

The ornamental design for a desoldering tool, substantially as shown and described.
